Primary Examiner — T. Chase Nelson*Assistant Examiner* — Kathleen M Sims(74) *Attorney, Agent, or Firm* — Clise, Billion & Cry, P.A.; Tim Clise(57) **CLAIM**

The ornamental design for a sock, as shown and described.

DESCRIPTION

FIG. 1 is a perspective view of a first embodiment of a sock showing our new design;

FIG. 2 is a front view thereof;

FIG. 3 is a rear view thereof;

FIG. 4 is right side view;

FIG. 5 is left side view;

FIG. 6 is top view; and

FIG. 7 is bottom view.

FIG. 8 is a perspective view of a second embodiment of a sock showing our new design;

FIG. 9 is a front view thereof;

FIG. 10 is a rear view thereof;

FIG. 11 is right side view;

FIG. 12 is left side view;

FIG. 13 is top view; and,

FIG. 14 is bottom view.

The broken line showing in the drawings are for environmental purposes only and form no part of the claimed design.
